(57) **CLAIM**

The ornamental design for a holder for point-of-sale terminals, as shown and described.

DESCRIPTION

1. Holder for point-of-sale terminals

1.1 : Perspective

1.2 : Left

1.3 : Top

1.4 : Bottom

1.5 : Back

1.6 : Front

1.7 : Right

The portions of the article shown in broken lines in Fig. 1.5 are for the purpose of illustrating environment and form no part of the claimed design.
